UNITED STATES PATENT OFFICE

HENRY E. WARREN, OF ASHLAND, MASSACHUSETTS, ASSIGNOR TO WARREN TELE-CHRON COMPANY, OF ASHLAND, MASSACHUSETTS, A CORPORATION OF MAINE

SPRING WINDING MECHANISM

Application filed November 17, 1930. Serial No. 496,046.

My invention relates primarily to a spring winding mechanism adapted for maintaining the spring of clocks and other spring operated devices wound to a substantially uniform condition. I prefer to employ an electric motor for winding the spring or springs and when this motor is of the synchronous type operated from a regulated frequency source of alternating current it may be and preferably is also employed, in combination with the other features of my invention, to assist in regulating or synchronizing the spring driven clock movement with the frequency of the alternating current supply, thereby increasing the reliability of apparatus as an accurate timing device.

In the form of the invention illustrated the electric motor winds the clock spring or springs through a cam actuated pawl operating upon a ratchet wheel connected to the spring winding arbor. A second pawl ordinarily prevents the ratchet wheel from backward rotation, but this second pawl is resiliently mounted and changes its position with respect to the teeth in the ratchet wheel as the counter tension of the clock spring approaches that corresponding to a fully wound condition. When the clock spring becomes substantially fully wound the position and movement of the retaining pawl is such that it no longer drops behind a tooth in the ratchet wheel as the latter is advanced and the mechanism ceases to wind the clock spring until its tension is decreased slightly. The same motor may actuate a pair of such devices, one for the winding of the main clock spring and the other for winding the spring which actuates the clock striking mechanism.

The features of my invention which are believed to be novel and patentable will be pointed out in the claims appended hereto. For a better understanding of my invention reference is made in the following description to the accompanying drawings, Fig. 1 of which shows a perspective exploded view of spring operated striking clockwork equipped with the spring winding mechanism of my invention wherein a synchronous motor is employed and which is also connected to the clock hands for synchronizing

purposes as will be explained; Fig. 2 is a more detailed view of the spring winding mechanism, Fig. 3 is an explanatory view of the ratchet wheel with the retaining pawl in the active or winding positions, and Fig. 4 is a modification of the invention.

Referring first to Fig. 1, 10 is a clock spring having its inner end fastened to a winding arbor 11 and its outer end connected to a gear 12 (free to turn on arbor 11) which gear is connected to drive the clock hands 13 through suitable gear trains comprising gears 14, 15 and 16 leading to the minute hand and gears 17, 18 and 19 leading to the hour hand. An ordinary escapement mechanism represented at 19 is connected to the minute hand shaft through a gear train represented by 23. It will be understood that the parts just described may represent any well known spring driven clock movement.

At 24 is a second spring with its inner end fastened to a winding arbor 25, and its outer end connected through gears 26 and 27 to a clock striking mechanism contained within the casing 28. Lever 29 represents a release lever for the strike mechanism operated every half hour from the clock train through cam 30. 31 and 32 respectively represent the gong and hammer of the strike mechanism. I have not shown the details of this strike mechanism as its construction constitutes no part of my invention but it will be understood that any well known strike mechanism is intended.

I will now describe the spring winding mechanism of my invention used to maintain the springs 10 and 24 wound to a substantially uniform tension. 33 represents a rotary motor which, if also used for assisting in keeping the clockwork synchronized, is of the electric synchronous type and may be similar to that described in my United States Patent No. 1,546,269, July 14, 1925. This motor is connected through gears 34 and 35 to a cam shaft 36 on which is mounted three cam eccentrics, two of which may be seen at 37 and 38. Upon these eccentrics are mounted cam pawls 39, 40 and 41. The pawls have bearing surfaces fitting the eccentrics and as the eccentrics are rotated the pawls are reciprocated. Pawls 40

and 41 actuate ratchet wheels 42 and 43 mounted on the winding arbors 11 and 25 of the springs 10 and 24 respectively. Each pawl has its center of gravity so positioned 5 with respect to its pivot point on its eccentric as to have its ratchet surface remain in contact with its corresponding ratchet wheel by the force of gravity. Thus the ratchet 40 is biased against ratchet wheel 42 by reason of 10 the fact that the ratchet tends to turn in a counter-clockwise direction about the bearing surface on its eccentric by reason of the greater weight of the enlarged or rear end of 15 the pawl located to the left of the cam surface.

The retaining pawls for ratchet wheels 42 and 43 are represented at 44 and 45 respectively and since the mounting and operation of both are similar an explanation of one will suffice. Pawl 44 is mounted on an arm 46 which is pivoted on the same axis of rotation as the spring winding shaft 11 on which the ratchet wheel is mounted. Rotational movement of arm 46 is limited by means of stop pin 20 47 mounted within the forked upper end of the arm. The position of this pin is adjustable to a limited extent and between it and the upper end of arm 46 is a resilient U-shaped spring 48. This spring is so positioned and tensioned that it tends to rotate 25 arm 46 in the direction in which the ratchet wheel is advanced in winding the spring and to hold the upper end of the arm 46 to the left against the stop pin 47, and it does so as represented in Fig. 3, when the clock spring 10 is wound to less than a predetermined tension. Under these conditions there is no movement 30 of arm 46 and the retaining pawl 44 drops behind a tooth in ratchet wheel 42 as the latter is advanced by each reciprocation of the ratchet 40 and the clock spring is thus slowly wound by energy received from the electric motor. However as soon as the clock spring becomes substantially wound the counter 35 torque becomes sufficient to rotate arm 46 against the tension of spring 48 causing arm 46 to rotate slightly in a clockwise direction and moving its top to the right until it rests against the other side of stop pin 47 as illustrated in Fig. 2. This counter torque of the clock spring acts through retaining pawl 44 when the advancing pawl 40 is retracted and causes the ratchet wheel 42 to rotate backward 40 the same distance it is advanced. Thus arm 46 and pawl 44 rotate slightly back and forth about shaft 11 as the pawl 40 reciprocates. The movement of the retaining pawl between the two positions is preferably slightly less than the spacing between the ratchet teeth 45 and the movement of the advancing pawl. As a result the winding of the clock spring ceases until its tension is relieved slightly from the escapement end. When the clock spring has run down sufficiently for spring 48, acting 50 through arm 46 and pawl 44, to overcome the

counter-torque, arm 46 is forced over to the winding position, Fig. 3, and the pawl and ratchet mechanism is again effective to wind the clock spring. Spring 48 is preferably so arranged that it exerts its strongest action in the winding position, Fig. 3; consequently there is no tendency for the arm 46 to rest in an intermediate position of equilibrium and the change of the mechanism from a winding condition to an ineffective condition and vice versa is positive.

In operation, the motor 33 is connected to a suitable source of supply and is normally in continuous operation. When either of the 55 springs 10 and 24 become unwound to a tension below that for which the apparatus is adjusted the corresponding control mechanism will function to make the pawl and ratchet spring winding mechanism effective. By proper adjustment the springs will be 60 maintained wound to a substantially uniform tension without danger of overwinding. The 65 clock springs will preferably be of sufficient length so that in case of failure of the source of supply for a few hours the clock will not 70 cease to function. When a plurality of 75 winding mechanisms are actuated by the same motor it will be desirable to so arrange the cams that the advancing strokes of the 80 cam pawls will occur at different points in the 85 rotation of the cam shaft so as to equalize 90 the load on the motor.

When the electric motor 33 is of the synchronous type connected to a regulated frequency source of power I prefer to use it for 100 directly assisting in the regulation of the clock. To this end I have represented the third pawl 39 and ratchet wheel 50 driven from the cam shaft 36. Ratchet wheel 50 is connected directly with the clock hands 105 through a suitable gear train represented in fact by 51 and it will be understood that when the frequency of the source of supply is correct the clock hands may be driven through 110 this gear train at the correct rate for the clock. Should the spring driven clock movement as determined by the escapement tend to be slow this connection to the synchronous motor will nevertheless force the clock to run at its proper rate. Should the clock 115 escapement tend to allow the clock to run fast the synchronous motor connection will produce a slight additional load or drag on the spring driven clock mechanism tending to correct it. However this connection to the 120 synchronous motor should contain a one-way drive such as an overrunning clutch, so that in case the motor stops, the spring driven clock movement will maintain the clock in operation. The ratchet wheel 50 and pawl 125 39 may serve to illustrate such overrunning clutch but it may be desirable to provide it nearer the clock end of the synchronous motor drive train.

It has been found that the spring winding 130

mechanism here described is entirely satisfactory in operation and provides a low cost, rugged, spring winding device for maintaining a substantially uniform spring pressure.

5 Fig. 4 shows another modification of the control means responsive to the tension of the spring for rendering the retaining pawls ineffective when the spring becomes substantially fully wound. Here the retaining pawl comprises a long resilient spring 52 with one end fixed at 53 and the other end lightly biased against the ratchet wheel 42. The spring pawl is bent slightly and rests near its center against a stop 54 when in its active 10 retaining position. When the counter torque of the clock spring (not shown) exceeds a predetermined amount spring pawl 52 will bend to the dotted line position with its center resting against a second stop 55. This 15 is the inactive position. It is evident that this spring pawl will exert its maximum resilient retaining force in the full line position. The stops 54 and 55 and the support 53 may be adjustable in position to obtain the most 20 desirable action.

What I claim as new and desire to secure by Letters Patent of the United States, is:

1. A spring winding device comprising in combination with a spring, a ratchet wheel 30 connected in winding relation to said spring, an advancing pawl for advancing said ratchet wheel to wind said spring, a motor for actuating said pawl, a retaining pawl for normally preventing backward rotation of said ratchet 35 wheel after being advanced, a support for said retaining pawl mounted for limited rotational movement about the axis of rotation of said ratchet wheel, and resilient means tending to rotate said support in the direction in which the ratchet wheel is advanced to wind the spring.

2. Apparatus for winding a spring to substantially a uniform tension, comprising in combination with a spring, a ratchet wheel 45 for winding the same, an advancing pawl for the ratchet wheel, means for actuating said pawl, a retaining pawl for the ratchet wheel, a support for the retaining pawl having limited rotational movement about the axis of rotation of said wheel, resilient means biasing the support in the direction in which the ratchet wheel is advanced in winding the spring, said resilient means being adjusted 50 to predominate over the counter torque of the spring, acting through the retaining pawl and support, so as to maintain the retaining pawl in a fixed active position until the spring is substantially fully wound and thereafter 55 to be overcome by the counter torque of said spring as the advancing pawl is retracted to allow the retaining pawl and its support to rotate backward and thereby prevent further winding of the spring until its tension 60 is reduced, said biasing means exerting its

minimum biasing force when overcome by the counter torque of the spring.

3. In apparatus of the character described a plurality of torsional springs, a rotary motor for winding said springs, a cam shaft 70 driven by said motor, cam pawls reciprocated by said cam shaft, a ratchet wheel in winding relation with each spring advanced by one of said cam pawls, retaining pawls for normally maintaining the advance of said ratchet wheels against the counter torques of the springs when the cam pawls are retracted, and resilient control means for each spring responsive to its counter torque for rendering the corresponding retaining pawl 75 ineffective when the spring is substantially fully wound, the control means for the different springs acting independently of each other.

4. In apparatus of the character described, a torsional spring, a clock movement driven by said spring, a synchronous electric motor for winding said spring and regulating said clock movement, a cam shaft driven by said motor, a pair of cam pawls reciprocated by said cam shaft a pair of ratchet wheels advanced by said pawls, one of said wheels being connected to regulate the clock movement and the other being connected to wind said spring, a retaining pawl for the last mentioned wheel for normally maintaining the advance of the wheel against the counter torque of the spring when the corresponding advancing pawl is retracted, and control 95 means responsive to the counter torque of the spring for rendering the retaining pawl ineffective when the spring is wound to a predetermined tension, said control means acting independently of the regulating function 100 of the synchronous motor on the clock movement.

In witness whereof, I have hereunto set my hand this 10th day of November, 1930.

HENRY E. WARREN.
